AIRPLANE

David W. Main, Denver, Colo.

Application September 7, 1942, Serial No. 457,623

1 Claim. (Cl. 244—9)

This invention relates to improvements in airplanes and has reference more particularly to an improved propeller mechanism. With the ordinary type of airplanes employing tractor propellers, considerable difficulty is experienced in taking off from the ground and with such airplanes a long air field is required in order that sufficient speed can be developed to create the necessary lifting force.

It is one of the objects of this invention to provide an airplane with propellers that shall be effective for producing a lifting, as well as a tractive, force, whereby the speed necessary to raise an airship from the ground can be reduced in an appreciable amount, thereby making it possible to take off from shorter airfields.

Another object of this invention is to produce an airplane having propellers positioned along the front edges of the wings, such propellers being rotatable about axes substantially parallel with the axis of the wings and provided with radial vanes which engage the air so as to produce both a lifting and a tractive force when rotated at high speeds in such a direction that the vanes move rearwardly below the axis of rotation.

In order to describe the invention so that its construction and mode of operation can be readily understood reference will be had to the accompanying drawing in which one specific embodiment of the invention has been illustrated, and in which:

Figure 1 is a perspective view showing a portion of an airplane in which the wings are provided with propellers of the type to which this invention relates;

Figure 2 is a front view of the airship shown in Figure 1 looking in the direction of arrow 2 and shows the construction to a slightly larger scale;

Figure 3 is a section taken along line 3—3, Figure 1 and shows the position of the propeller with respect to a cross section of the wing;

Figure 4 is an enlarged cross sectional view taken along line 4—4, Figure 1, and shows a slightly modified form of propeller and illustrates in greater detail the construction;

Figure 5 is a top plan view of the rear end of a plane showing the transverse stabilizing vanes thereof;

Figure 6 is a top plan view of the modified form of airship in which a plurality of pairs of wings are employed;

Figure 7 is a side elevation of the airplane shown in Figure 6;

Figure 8 shows a modified form of propeller construction, and

Figure 9 shows an oscillating form of propeller.

In the drawing reference numeral 10 designates the fuselage of an airplane. The exact construction of the fuselage has not been shown because it is independent of the invention covered by this application.

The ordinary motor usually provided for airships, has been designated by reference numeral 11 and the tractor propeller by numeral 12. The engine and propeller have been shown diagrammatically as they are of usual construction and their relation to an airship is well known.

Extending laterally from the fuselage are wings 13 one pair being shown in Figures 1 and 2. The wings may be of the usual construction and have a cross section like that shown in Figure 3. The diagonals 14 indicate the truss members usually provided in airplane wings.

The wings differ from the ordinary wings in this, that the front edges are provided with elongated openings 15 in which are positioned elongated propellers whose hubs have been designated by reference numerals 16. Extending radially from the hubs are blades 17. These blades may be longitudinally straight and have the greater portion of their areas lying in planes containing the axis of rotation. Or, they may be helical as shown in Figures 1 and 2, the latter being preferable.

A cross section of the blades may be like that shown in Figure 4 in which the portion nearest the hub is radially straight and terminates in a forwardly inclined edge 18. The center of curvature of the inclined edges lies to the front of the blade when the edge is at the top and to the rear when the blade is at the bottom, as can be clearly shown from Figure 4. In Figure 3, the blades have been shown arcuate and curved about the centers c. Each wing has a portion of its front edge cut away so as to provide access to the space occupied by the propeller. An arcuate metal wall 19 extends upwardly from the lower wall 20 of the wing as shown in Figure 4 and an arcuate wall 21 has its lower and rearwardly positioned edge overlapping the wall 19 and extends upwardly to a point indicated by reference numeral 22. The lower rear edge of the wall 21 is provided with gear teeth 23 that are engaged by a pinion 24 which is secured to a shaft 25 that can be rotated by suitable means accessible to the pilot. The curved or arcuate

blade 17 is provided with a gear teeth 26 that are engaged by a pinion 27 which is secured to a shaft 28 that can be rotated by suitable means accessible to the pilot. The curved or arcuate

blade 17 is provided with a gear teeth 29 that are engaged by a pinion 30 which is secured to a shaft 31 that can be rotated by suitable means accessible to the pilot. The curved or arcuate

blade 17 is provided with a gear teeth 32 that are engaged by a pinion 33 which is secured to a shaft 34 that can be rotated by suitable means accessible to the pilot. The curved or arcuate

blade 17 is provided with a gear teeth 35 that are engaged by a pinion 36 which is secured to a shaft 37 that can be rotated by suitable means accessible to the pilot. The curved or arcuate

wall 21 is provided with a plurality of openings 26 through which air may escape as indicated by arrows 27. The top wall of the wing is provided with a plurality of openings 28 formed by slitting the material and bending a portion thereof upwardly as indicated by reference numeral 29. The arrows 30 designate the direction and position of the air stream that passes over the wing. The area between the arrows 30 and the top of the wing, which area has been designated by reference numeral 31, is greatly rarified, approaching in some cases quite close to a vacuum. Due to the low pressure in area 31 the air thrown outwardly from the rotating propeller, as indicated by arrows 29, will pass outwardly in the direction of arrow 28, thereby reducing the air density between the propeller blades, if desired.

Each propeller is secured to a drive shaft which has been designated by reference numeral 32 in Figure 4. The shaft 32 is rotated in the direction of the arrow in Figure 1 and in a counterclockwise direction when viewed as in Figures 3 and 4, by power from the engine 11. This power is transmitted to the shaft by any suitable motion transmitting means and as illustrative of such means shaft 32 in Figure 1, has been shown as provided with a gear wheel 33 that is in mesh with a gear wheel 34 carried on shaft 35. The motor shaft 36 is provided with a bevel gear 37 that cooperates with a pinion 38. Whenever the engine operates to turn propeller 12, it will also rotate the propellers located in the recesses 15 of the blades.

We will now refer to Figure 4, from which it will be seen that the blades 17 are rotated in a counterclockwise direction. When the blades arrive at the end of wall 21, which has been designated by reference numeral 22, air will enter the space between two adjacent blades and since these are rotating at a high velocity, their reaction when striking the vertically stationary air currents will be to produce a force having a component tending to lift the plane. These components of force have been designated, for the purpose of illustration, in Figure 4, by reference numeral 39. As the blade moves downwardly, the lifting component will increase, becoming maximum when the blade is in a horizontal position. The lifting component will then decrease and another force will be produced which tends to move the airship forwardly. The effect of the rapidly rotating longitudinally extending propellers is therefore to produce a lifting force and in addition a tractive force that supplements the tractive force produced by the propeller 12.

It is evident that during the time that the blades move from the lower end of the arcuate wall 19 to the forward and upper end of wall 21, they will exert no appreciable force tending to move the airship in any direction, with the exception of the tractive forces produced by the flow of air through the openings as indicated by arrows 27. The centrifugal forces exerted by the rotating propeller, as well as the suction due to the rarified area above the wing tends to exhaust the air from between the blades of the propeller so that, when the latter move beyond the edge 22, the air in which the ship is moving will rush into the rarified space in sufficient volume to produce an appreciable resistance by its inertia effected.

It is evident that if the cylindrical wall 21 is rotated in a counterclockwise direction from the position shown in Figure 4, it will shield the

blades through a greater arc and it will therefore prevent air from coming into contact with the blades until they have reached such a position that no retarding force component is created.

In landing it may be desirable to rotate the wall 21 in a clockwise direction so as to neutralize to some extent the tractive effort of the blades 17. By adjusting the rotary position of wall 21, the effect produced by the rotating propeller can be modified so as to produce effects most suitable for the conditions under which the airplane is operating.

The invention has been illustrated in connection with the airplane having one pair of wings, as is most usual. It is possible, however and sometimes desirable, to provide an airplane fuselage like that designated by 10a in Figures 6 and 7, with a plurality of pairs of wings such as have been designated by reference numerals 13a, and to provide each wing with a propeller like that shown in Figures 1 to 4. It is also possible to provide the stabilizing blades 40, shown in Figure 5, with rotating propellers like those shown on the drawing and above described.

Where a plurality of pairs of wings are employed, as in Figures 6 and 7, they may be spaced at different vertical distances compared to the longitudinal axis of the fuselage, and an airplane thus constructed will have a considerable lifting force produced by the action of the propellers and can therefore take off from the ground at a much lower space than an airship provided with a single pair of blades.

Attention is called to the fact that in Figures 1 and 2 the propellers have been shown as provided with helical vanes curved as shown in Figures 3 and 4. Such vanes are believed to be preferable to straight vanes, but the helical construction is not essential to successful operation and has merely been illustrated to show what is at present believed to be the preferred construction.

It will be observed from Figures 1 and 2 that the auxiliary propellers are frustoconical in shape, tapering outwardly. This shape is due, primarily, to the fact that the ordinary airplane wings are thicker nearer the fuselage than towards their ends and the propellers have been constructed so as to conform to the shape of the wings.

In the present construction the arcuate wall 21 has been shown as extending along the entire length of the propellers and movable as a unit through the action of the rack and pinion mechanism illustrated in Figure 4. At times it may be preferable to make the curved wall 21 in two or more sections and to rotate each independently of the other by means like that shown and described herein. By having the wall 21 in several sections, each independently adjustable, a greater variety of effects can be produced than when a single wall is employed.

From the above description it will be apparent that an airplane provided with auxiliary vanes as shown and described can take off at a lower speed than a similar airplane not having auxiliary propellers as the latter exert a considerable lifting force, or the airship may take off with a greater load than an airplane not so constructed and equipped.

It is to be understood that the invention has been illustrated in a more or less diagrammatic manner as the exact size and shape of the plane,

the degree of taper of the auxiliary propellers, and the pitch of the blades can be varied to obtain the best results. When the pitch is decided it may be possible to make the propellers of double or triple pitch. But for the purpose of illustration, the long pitch has been selected.

Where the auxiliary propellers are provided on airplanes having motors attached to the blades, the auxiliary propellers may be made in sections position on both sides of the motor mounting.

In Fig. 8 a propeller of slightly modified form has been shown. In this embodiment the blades 17a are of opposite pitch.

In Fig. 9 a further modification has been shown in which the propeller is oscillated instead of rotated. The power for oscillating the propeller is supplied by a crank 41 that transmits it to the propeller by means of a connecting rod 42.

Having described the invention what is claimed as new is:

An airplane wing having an elongated recess in its leading edge, an elongated propeller provided with radial vanes mounted in the recess for rotation about an axis substantially parallel with the longitudinal axis of the wing, the upper surface of the wing having a longitudinally extending opening positioned adjacent the center line of the wing, the opening being in communication with the recess, whereby when the propeller is rotated, air will flow between the recess and the slot in the top of the wing and means for changing the area of the propeller exposure 15 at the front of the recess.
